US00D777405S

(12) United States Design Patent (10) Patent No.: US D777,405 S
Bacal (45) Date of Patent: * Jan. 31, 2017

(54) BIFURCATED GARMENT

(71) Applicant: JB CLOTHING CORPORATION,
Henderson, NV (US)

(72) Inventor: Jerry Bacal, Henderson, NV (US)

(73) Assignee: JB CLOTHING CORPORATION,
Henderson, NV (US)

() Term: 15 Years

(21) Appl. No.: 29/550,689

(22) Filed: Jan. 6, 2016

(51) LOC (10) Cl. 02-02

(52) U.S. Cl.

USPC D2/742

(58) Field of Classification Search

USPC D2/742, 731, 851, 730, 735, 738; 2/227,
2/69; 224/222, 238; D15/150

CPC A41D 27/20; A41D 1/06; A61F 5/445

(57) CLAIM

The ornamental design for a bifurcated garment, as shown and described.

DESCRIPTION

FIG. 1 is a front perspective view of the bifurcated garment. FIG. 2 is a rear perspective view of the bifurcated garment.

FIG. 3 is a front view of the bifurcated garment.

FIG. 4 is a rear view of the bifurcated garment.

FIG. 5 is a right side view of the bifurcated garment; and, FIG. 6 is a left side view of the bifurcated garment.

The diagonal shading represents denim and the stippled shading represents a stretch fabric.

The short dashed lines represent portions of the bifurcated garment that form no part of the claimed design.

The long dashed lines represent portions of the bifurcated garment that form no part of the claimed design.

The dot dashed lines represent unclaimed boundaries of the design.

1 Claim, 5 Drawing Sheets
